UNITED STATES PATENT OFFICE.

JOSEPH H. BOURGON, OF DETROIT, MICHIGAN, ASSIGNOR TO THE STUDEBAKER CORPORATION, OF SOUTH BEND, INDIANA, A CORPORATION OF NEW JERSEY.

WEATHER-EXCLUDING MEANS.

Application filed July 28, 1923. Serial No. 654,496.

To all whom it may concern:

Be it known that I, JOSEPH H. BOURGON, a subject of George V, King of Great Britain and Ireland, and resident of Detroit, in the county of Wayne and State of Michigan, have invented certain new and useful Improvements in Weather-Excluding Means, of which the following is a specification.

10 This invention relates to closures for openings, such, for example, as closures for doors and windows in automobiles, carriages and the like, and has for its object to provide means to prevent rain, snow and other 15 elements from entering the chamber formed in the body when the closure is placed in closed position.

A further object is to provide a resilient strip of material between the closure and 20 the body to compensate for varying distances between the closure and the body.

A further object is to provide a resilient strip of material which may be secured in the chamber formed in the body and which 25 is adapted to form a weather excluding means between the body and lower edge of the closure when the window is in closed position.

A further object is to provide a weather 30 strip of novel construction which may be used as a weather excluding means between mating surfaces.

A still further object is to provide a resilient material such, for instance, as rubber 35 which has a plurality of extending split flexible elements adapted to compensate for irregularities in mating surfaces.

Further objects and objects relating to 40 details of manufacture and construction will definitely appear from the detailed description to follow, in which

Figure I is a perspective view of a door showing the closure in partially closed position.

45 Figure II is an enlarged sectional view taken on the line II-II of Figure I, but showing the closure in extended position.

Figure III is a fragmentary perspective view of the resilient weather strip.

50 Like reference numerals, refer to like parts throughout the several views and the sectional view is taken looking in the direction of the arrows at the end of the section line.

55 Referring to the drawing, the door 1 is

provided with side rails 2 and a top rail 3. An opening 4 is formed in the door which may be closed by a glass or other means 5, the side edges of which are adapted to slide in ways 6 formed in the side rails 2. The glass or closure may be raised and lowered by any convenient means as, for example, a lever 7 operated by a handle (not shown) the lever having a roller 8 mounted at its outer end and adapted to ride on a U-shaped binding strip 9 secured along the lower edge of the glass 5. An angle bar 10 is secured by spot welding or other means to the U-shaped member 9, the lower flange of which is adapted to extend below the roller 8 and to contact with the same when it is desired to lower the window. In raising the window the roller 8 contacts with, or rides on, the U-shaped member 9 to assist in raising the window.

The door 1 is provided with a horizontal cross-frame member 11 on its outer side, which may have any suitable covering 12, such as sheet metal or aluminum, the edge 13 of which extends beyond and inwardly from the upper edge of the cross-frame member 11. To present a smooth and finished appearance the inwardly extending portion 13 may have its free end rolled and returned on itself as indicated at 14. The U-shaped strip 9 on the lower edge of the glass 5 is provided with a rolled edge or extending portion 15 which extends on that side of the glass adjacent the extended portion 13 of the door covering, for a purpose which will hereinafter be described.

A weather strip 16 formed of rubber or other suitable material has a body portion 17 and a plurality of flexible projections 18 extending inwardly from the upper edge of the body portion 17. The weather strip 16 may be secured to the frame member 11 by screws or other suitable means 19 and is secured in such position that the upper edge of the upper flexible projection 18 will lie against the under surface of the turned edge portion 14 of the door covering 12. The flexible inwardly extending projections 18 of the weather strip 16 are preferably so formed that their vertices are spaced apart until such time as pressure is applied against these projections to force their mating surfaces together. As the weather strip 16 is placed directly beneath the projection 13, it will be seen that as the window is elevated

to its closed position the projection or rolled edge 15 extending from the U-shaped binding strip 9 on the lower edge of the glass 5 will contact with and force the lower distending projection 18 against the upper projection extending from the weather strip, thus closing the space between their vertices and fill the gap left between the extending portion 13 of the body covering and the 10 rolled edge or projection 15 on the binding strip 9. Should either of the projections on the body or the window be bent or become distorted, or the projection 15 on the window and the projection 13 on the body not 15 be in perfect alignment along the entire length, the great flexibility of the weather strip is such that the projections 18 will yield to such irregularity and will seal the opening regardless of such shape.

20 From the foregoing description this device should be readily understood, the projection 13 on the door covering 12 is adapted to extend inwardly from the cross-member 11 to a point adjacent the side of the glass 25 or closure 5. When the glass is raised to a closed position the extension 15 provided on the binding or wear strip 9 at the lower edge of the glass is extended to a position slightly removed from the projection 13. The above 30 weather strip having its body portion secured to the frame cross-member and its flexible diverging projections adapted to lie between the projections 13 and 15 and be squeezed or forced together to form a tight joint and 35 seal the opening between these projecting portions. A chamber is formed in the door within which the closure rests when in its lowered or open position, and this weather strip will not only prevent water or other 40 substances from entering the chamber so formed, when the glass is raised to closed position, but will also prevent rattle of the closure.

While I have shown and described a 45 weather strip as being applied to an automobile door and adapted to exclude the elements of the weather and compensate for irregularity in mating surfaces of the relative parts, it is to be understood that this 50 weather strip may be used where found desirable, and where convenient to apply the same. I also wish it to be understood that the drawing and description is only for the purpose of illustration and I do not 55 wish my invention confined to the precise details of construction shown and described herein, but I do wish this invention interpreted broadly, as well as specifically, and herewith confine myself to only such limitations as are pointed out in the appended 60 claims.

Having thus described my invention what I wish to claim and secure by Letters Patent is:

65 1. In a device of the class described, a

frame having a projection thereon forming a finish for an opening therein, a slidable closure for said opening, a projection on said closure, and a resilient weather strip between said projections on said frame and 70 closure, said weather strip comprising a body portion and a plurality of projections thereon, said projections contacting with said projections on said frame and closure and with each other when said closure is 75 in closed position.

2. In a device of the class described, a frame having a projection thereon forming a finish for an opening therein, a slidable closure for said opening, a projection on said closure, and a resilient weather strip between said projections on said frame and closure, said weather strip comprising a body portion and a plurality of extending 80 projections thereon having the greatest sectional areas at their bases, said projections contacting with said projections on said frame and closure and with each other when said closure is in closed position.

3. In a weather strip, a body portion, and a projection extending therefrom, said projection comprising a plurality of distending members of diminishing cross sectional area adapted for movement relative to each other, to contact with each other to provide weather 85 excluding means.

4. In a weather strip, a body portion, and a projection at one end thereof comprising a plurality of substantially V-shaped members whose vertices are normally spaced 100 apart when in inoperative position to provide a V-shaped groove between said members, the inner faces of said members being adapted to contact with each other when in operative position.

5. In a weather strip, a body portion, and a plurality of distending projections of diminishing cross sectional area extending therefrom and at an angle thereto, the vertices of said projections being normally spaced apart, when in inoperative position and contacting when in operative position.

6. In a closure for windows and the like, the combination of a frame member having a projection at its upper edge, a 115 slidable closure having a projection adjacent its lower edge, and a resilient member having a body portion secured to said frame member and a plurality of projections extending from said body portion, one of said projections on said resilient member contacting with a face of the projection on said frame and the other of said projections being adapted to contact with the projection on said closure to close the opening between said frame and closure when said closure is 120 in closed position.

7. In a closure for windows and the like, the combination of a frame member, a projection on said frame member, a 125 slidable

closure, a projection on said closure, and a resilient member secured to said frame member and having a plurality of substantially V-shaped projections extending therefrom, 5 said V-shaped projections extending between the projections on said frame member and said closure and adapted to close the opening between said last named projections when said closure is in closed position.

10 8. In a door having a frame and an opening therein, a projection on said frame extending inwardly therefrom, a slidable closure for said opening, a member surrounding the lower edge of said closure and having a 15 projection thereon, a resilient strip having a body portion and a plurality of projections extending from one end thereof, one of said projections on said resilient strip resting against the projection on said closure 20 when said closure is in closed position.

9. In combination, a frame having an

opening therein, a closure for said opening, a projection on said frame and said closure, and a weather strip comprising a body portion and a plurality of flexible elements extending between said projections on said frame and said closure, one of said flexible elements being normally out of engagement with said projection on said closure when said closure is in open position, the other of 25 said flexible elements normally contacting with said projection on said frame, said flexible elements being adapted to contact with and fill the opening between said projections on said frame and closure when said closure 30 is in closed position.

Signed by me at Detroit, Michigan, U. S.
A. this 21st day of July, 1923.

JOSEPH H. BOURGON.
